(***) Term: **14 Years**

(57) **CLAIM**

(21) Appl. No.: **29/339,815**

The ornamental design for a unit for source separation and temporary storage of waste, as shown and described.

(22) Filed: **Jul. 8, 2009**

DESCRIPTION

(30) **Foreign Application Priority Data**

Jan. 8, 2009 (NO) 20090016

FIG. 1 is a perspective view of the claimed design.

(51) **LOC (9) Cl.** **09-09**

FIG. 2 is a top view of the claimed design.

(52) **U.S. Cl.** **D34/1**

FIG. 3 is a front view of the claimed design.

(58) **Field of Classification Search** D34/1,

FIG. 4 is a rear view of the claimed design.

D34/5, 6, 7, 8, 9, 10, 11; 220/908-913

FIG. 5 is a left side view of the claimed design; and,

See application file for complete search history.

FIG. 6 is a right side view of the claimed design.
